UNITED STATES PATENT OFFICE.

JOSEPH S. LAPISH, OF AMERICAN FORK, UTAH TERRITORY.

AIR-BRAKE.

SPECIFICATION forming part of Letters Patent No. 399,420, dated March 12, 1889.

Application filed August 4, 1888. Serial No. 282,007. (No model.)

To all whom it may concern:

Be it known that I, JOSEPH SETTLE LAPISH, of American Fork, in the county of Utah and Territory of Utah, have invented a new and 5 Improved Air-Brake, of which the following is a full, clear, and exact description.

The invention consists in certain improvements, which will be hereinafter pointed out.

Reference is to be had to the accompanying 10 drawings, forming a part of this specification, in which similar letters of reference indicate corresponding parts in all the figures.

Figure 1 is an inverted plan view of the improvement as applied to the car. Fig. 2 is 15 a transverse sectional elevation of the same on the line *x x* of Fig. 1. Fig. 3 is an inverted plan view of the coupling as applied between two cars. Fig. 4 is a sectional side elevation of the same on the line *y y* of Fig. 3. Fig. 5 is 20 an enlarged side elevation of the valve-chest. Fig. 6 is a plan view of the same with the top cover removed. Fig. 7 is a sectional side elevation of the same on line *z z* of Fig. 6. Fig. 8 is a similar view of the same on the line *w w'* of Fig. 6. Fig. 9 is a sectional side elevation of the same on the line *w' w'* of Fig. 6. Fig. 10 is a transverse section of the same 25 on the line *u u* of Fig. 6. Fig. 11 is an enlarged plan view of the coupling, showing one-half in section. Fig. 12 is a transverse section of the same on the line *v v* of Fig. 11. Fig. 13 is a face view of one-half of the coupling. Fig. 14 is a sectional end elevation of the same on the line *t t* of Fig. 13. Fig. 15 is 30 a sectional side elevation of one of the valves in the said coupling. Fig. 16 is an inverted sectional plan view of the same on the line *s s* of Fig. 16, and Fig. 17 is a sectional plan view of the same on the line *s s* of Fig. 15.

On the bottom of each car are held transversely the two pipes B and C, of which the pipe B is the air-supply pipe, and the other pipe, C, is the operating-pipe for actuating the 35 brake mechanism. Both pipes B and C are connected, in the usual manner, with the main reservoir on the locomotive, and both pipes are under the control of the engineer by a suitable engineer's valve. From the pipes B and C lead the branch pipes B' and C', respectively, to a valve-chest, D, secured at one end of the auxiliary air-reservoir E,

held on the bottom of the car, and supporting at one end the brake-cylinder F, in which operates, in the usual manner, the piston F', connected by its piston-rod F² with the lever G of the brake mechanism, of any approved construction.

The brake-cylinder F is divided from the auxiliary air-reservoir E by a transverse partition, E', held at the end of the said reservoir E, as is plainly shown in Fig. 9. The valve-chest D is provided with a top cover, D', and with a bottom cover, D². The branch pipe B' from the air-supply pipe B connects in the valve-chest D with an aperture, a, which leads to a check-valve, II, held to slide in a chamber, II', formed in the valve-chest D, and connected by a channel, a', with the interior of the auxiliary air-reservoir E. When the engineer desires to charge the auxiliary air-reservoir E, he lets air from the main reservoir pass into the air-supply pipe B, from which air passes through the branch pipe B' into the aperture a and against the under side of the check-valve II, so that the latter is lifted 70 and the air can pass through the channel a' into the reservoir E, in which the air is stored.

The operating-pipe C is connected by its branch pipe C' with an opening, b, formed in the valve-chest D. The opening b leads to a vertical channel, b', which connects at its upper end by the channel b² with a cylindrical chamber, I', in which is held to slide vertically a piston, I, carrying on its under side a stem, I², adapted to be seated on top of an opening, d, leading into a channel, d', extending horizontally in the valve-chest D and leading at one end into a chamber, J', connected with the cylindrical chamber J², in which operates a piston, J, connected by a fluted stem, J³, with a piston, K, held to slide vertically in a chamber, K', formed in the said valve-chest D.

The stem J³ passes through the chamber J' and through an opening, e, between the chambers J' and K'. The lower end of the vertical channel b' leads into a groove, b³, formed in the bottom cover, D², of the valve-chest D. The groove b³ leads into the cylindrical chamber J² at the under side of the piston J. The inner end of the horizontal channel d' connects with a pipe, L, extending through the

auxiliary reservoir E, and opening at the inner end of the brake-cylinder F by passing through the partition E' of the auxiliary reservoir E, as is plainly shown in Fig. 9. The 5 valve-stem I² of the valve I passes through a transverse slot, c, formed in the valve-chest D, and leading to the outside at each end. The opening d, connected with the horizontal channel d', also connects with the said transverse slot c whenever the valve I is lifted. The upper end of the chamber H' is connected by an opening, f, with the chamber K', as is plainly shown in Fig. 6.

In order to actuate the brakes, the engineer 15 permits air to pass through the operating-pipe C into the branch pipe C', and from the latter the air passes through the opening b into the vertical channel b'. The air passes from the upper end of the latter, by means of the 20 channel b², into the chamber I', acting on top of the piston I, so that the latter is pressed downward and the lower end of its valve-stem I² closes the opening d. Part of the air then passes from the lower end of the channel d' 25 through the groove b³ into the chamber J² and against the under side of the piston J, which is thus forced upward, so that the valve K is unseated, and air from the auxiliary reservoir E can pass through the channel a', the chamber H', and the channel f into the said chamber K' and through the opening e into the chamber J', the fluted stem J³ permitting such movement of air from the chamber K' to the chamber J'. The air then passes from 30 the latter through the horizontal channel d' into the pipe L, which leads into the brake-cylinder F, so that the piston F' is forced outward, actuating the brake mechanism, and thus applying the brakes. In order to release the brakes, air is released from the operating-pipe C, so that the valve I is raised by the pressure of air in the brake-cylinder F, the pipe L, and the channel d', and the air from the brake-cylinder can escape through 35 the said pipe L, the channel d', and the opening d into the transverse slot c and into the open air, thus releasing the brake mechanism and the brakes.

The auxiliary air-reservoir E is provided 40 on top with a check-valve, N, establishing connection between the auxiliary reservoir E and the pipe N', leading to a second auxiliary reservoir, O, secured to the under side of the car A, as is plainly shown in Figs. 1 and 2. The pipe N' is connected by a pipe, N², with the operating-pipe C, and in the said pipe N² is held a valve, N³, carrying on its stem a lever, N⁴, pivotally connected at one end with a rod, N⁵, leading to one end of the car A, and 45 likewise connected at its other end with a rod, N⁶, leading to the other end of the said car A. Thus when the lever N⁴ is turned the valve N³ is shifted, and so connects the pipe N' with the operating-pipe C, or disconnects it from the same.

The ends of the pipes B and C at each end of the car A are connected by flexible tubes

B² and C², respectively, with a coupling, P, connecting by similar flexible tubes, B² and C², with the ends of the pipes B and C on the 70 next following car. (See Figs. 3 and 4.)

The coupling P may be of any approved construction, but so arranged as to transmit the air in the pipe B on one car to the pipe B on the other car, and in a similar manner 75 to transmit the air to the pipe C on one car to the pipe C on the other car. The construction of the coupling shown in Fig. 2 consists of two parts, P' and P², each of which is provided with the channels P³ and 80 P⁴, respectively, connecting with the flexible tubes B² and C² of the pipes B and C. Each of the channels P³ and P⁴ leads to a valve, Q or R, respectively held in the respective part P' or P² of the coupling P, and pressed 85 inward by a suitable spring, Q' or R', so that the two valves Q in the coupling abut against each other, as shown in Fig. 12, and the valves R press against each other, as is plainly shown in the same figures, and in a 90 similar manner. The valves Q and R are so arranged that if the coupling breaks from any cause the spring Q' or R' forces the respective valve R or Q outward, so as to seat the same on its seat in the part P' or P², 95 whereby the channel P³ or P⁴ is closed.

On each of the parts P' or P² is secured a hook, S, engaging a slide, T, mounted to move longitudinally in suitable guideways secured on the outside of the respective parts P' or 100 P². The outer end of each slide T is pivotally connected with the end of the rod N⁵ or N⁶, previously mentioned—that is, the rod N⁶ at one end of the car A connects by the respective slide T with the hook S of the part 105 P' or P² supported on the next following car, so that when the coupling P breaks the respective part exerts a pull on the rod N⁶, so as to turn the lever N⁴, operating the valve N³, which opens the connection between the pipe 110 N' and the operating-pipe C, thus admitting air from the second auxiliary reservoir O to the operating-pipe C, and the latter, in the manner above described, operates the brake mechanism of the respective car. Thus it 115 will be seen that when a train breaks apart the air from the second auxiliary reservoir O fills the operating-pipe C, which is shut off from the main reservoir by the respective valve R being forced outward by its spring 120 R' by the breaking of the coupling P. As soon as the train breaks apart and the coupling P is broken the brake mechanism of the cars is actuated, as the said operating-pipe C is charged with air from the second auxiliary 125 reservoir O, in the manner above described—that is, the air from the auxiliary reservoir O passes through the pipe N', the pipe N², and the valve N³ into the operating-pipe C, and from the latter by the branch pipe C' into 130 the valve-chest D, from which it passes into the brake-cylinder F, as above described, in order to actuate the brake mechanism G.

Having thus described my invention, what I

claim as new, and desire to secure by Letters Patent, is—

1. In an air-brake, an operating-pipe and an air-supply pipe, both connected with the main reservoir and under the control of the engineer, in combination with a valve-chest connected by branch pipes with the said air-supply pipe and the said operating-pipe, an auxiliary air-supply connected with the said air-chest, and a brake-cylinder connected with the brake mechanism, and also with the said valve-chest, a second auxiliary reservoir connected with the first-named reservoir, a pipe connecting said auxiliary reservoir with the said operating-pipe, a valve held in the said pipe to connect the operating-pipe with or disconnect it from the said auxiliary reservoir, and a coupling held at each end of

the car and adapted to operate the said valve, substantially as shown and described. 20

2. In a car-brake, the combination, with two auxiliary reservoirs located on each car and connected by a pipe, of an operating-pipe connected with the said auxiliary reservoirs, a valve located in the connection between the 25 said operating-pipe and the said auxiliary reservoirs, and a coupling located between two adjoining cars and provided with two parts, of which one is connected by a rod with the said valve, to actuate the same in case of the breaking apart of the two cars, substantially as shown and described.
